(57) **CLAIM**

The ornamental design for a switch plate for rocker-type switch, as shown and described.

DESCRIPTION

FIG. 1 is a perspective view of a switch plate for rocker-type switch showing our new design.

FIG. 2 is a top view thereof.

FIG. 3 is a front view thereof.

FIG. 4 is a bottom view thereof.

FIG. 5 is a back view thereof.

FIG. 6 is a right side view thereof.

FIG. 7 is a left side view thereof.

FIG. 8 is a perspective view of a second embodiment of a switch plate for rocker-type switch showing our new design, for a dual switch arrangement.

FIG. 9 is a top view thereof.

FIG. 10 is a front view thereof.

FIG. 11 is a bottom view thereof.

FIG. 12 is a back view thereof.

FIG. 13 is a right side view thereof; and,

FIG. 14 is a left side view thereof.

The broken lines in the drawings representing the person figure and mounting fastener holes are for illustrative purposes only and form no part of the claimed design.
